UNITED STATES PATENT OFFICE.

HARRY M. PFLAGER AND CLARENCE H. HOWARD, OF ST. LOUIS, MISSOURI,
ASSIGNORS TO AMERICAN STEEL-BODY DOUBLE-BOLSTER CO., OF ST.
LOUIS, MISSOURI, A CORPORATION OF NEW JERSEY.

CAR-TRUCK.

No. 799,085.

Specification of Letters Patent.

Patented Sept. 12, 1905.

Application filed June 21, 1905. Serial No. 266,274.

To all whom it may concern:

Be it known that we, HARRY M. PFLAGER and CLARENCE H. HOWARD, citizens of the United States, residing at St. Louis, in the State of Missouri, have invented a new and useful Improvement in Car-Trucks, of which the following is a specification.

Our invention, which is in the nature of an improvement on that for which Letters Patent of the United States were granted to us November 8, 1904, No. 774,492, for an improvement in car-trucks, relates to the center-plate of the car-truck bolster and has for its object to enable the center-plate to be vertically adjusted for taking up the set of the bearing-springs and wear of the wheels, and thereby maintain a constant level of the car-body.

Our invention consists in features of novelty, as hereinafter described and claimed, reference being had to the accompanying drawings, forming part of this specification, whereon—

Figure 1 is a top plan of a car-truck bolster having our improved center-plate; Fig. 2, a vertical longitudinal section through the bolster and center-plate on line 2 2 in Fig. 1; Fig. 3, a vertical transverse section thereof, partly broken away, on line 3 3 in Fig. 1; and Fig. 4, a similar view thereof in the adjusted position of the center-plate.

Like letters and numerals of reference denote like parts in all the figures.

a is the center beam or bolster of a car-truck, (preferably six-wheeled,) which spans the spring-beams *b* (indicated by broken lines in Figs. 1 and 2) and is similar in construction and arrangement, except where otherwise specified, to that described in the said Letters Patent, or it may be otherwise configured, as found most suitable.

c is the truck center-plate, which in lieu of being cast integral with the body of the bolster *a*, as in the said Letters Patent, is of separate construction, removably fixed to the bolster and perforated centrally for the king-bolt (not shown) in the usual manner. The center-plate *c* is formed or provided with a

preferably rectangular (circular, elliptical, or other shaped) base-plate 1, which is adapted to fit and slide vertically at its circumference or perimeter within a correspondingly-shaped pocket or recess 2, formed in the top of the bolster *a*, at the middle thereof, and having its sides or surrounding wall extending upward to a suitable height therefrom.

Through registering holes 3 4 in the base-plate 1 and bottom of the pocket 2, respectively, pass bolts 5, which in the initial position of the several parts of the truck secure the center-plate *c* directly to the bottom of the pocket 2, as seen particularly in Fig. 3.

By this construction as the main bearing-springs of the car-truck settle and the wheels become worn a constant level of the car-body is maintained by removing the bolts 5 and raising the center-plate *c* in the pocket 2 accordingly, a liner 6, of wood or other suitable material, in such case being placed within the pocket 2 between the bottom thereof and the base-plate 1 of the center-plate *c*, and by substituting longer bolts 5' for the bolts 5 the center-plate *c* is thereby held at the adjusted level, as seen particularly in Fig. 4, whereas when the truck center-plate is cast integrally with the bolster, as described in the said patent, the level of the car-body is rendered variable.

A great advantage of this construction is that by fitting the base-plate 1 of the center-plate *c* closely within a pocket 2, which is integral with the bolster *a*, the center-plate *c*, while capable of vertical adjustment, is rigidly held in place and shearing strain on the bolt 5 or 5' prevented.

What we claim as our invention, and desire to secure by Letters Patent, is—

1. In a car-truck, the combination with the truck-bolster having a pocket in the top, of a center-plate perforated for the king-bolt, the said plate being held by and adapted to be vertically adjustable within the said pocket, and means for removably fixing the center-plate to the said bolster, substantially as described.

2. In a car-truck, the combination with the

truck-bolster having a pocket in the top, of a center-plate perforated for the king-bolt and having a base-plate adapted to slidably fit within the said pocket, and means for remov-
5 ably fixing the center-plate to the said bol-
ster, substantially as described.

In testimony whereof we have signed our

names to this specification in the presence of two subscribing witnesses.

HARRY M. PFLAGER.
CLARENCE H. HOWARD.
